UNITED STATES PATENT OFFICE

123,394

DESIGN FOR A CLOTHES HANGER

Margaret Brown Dunlap, Lubbock, Tex.

Application May 31, 1940, Serial No. 92,719

Term of patent 3½ years

To all whom it may concern:

Be it known that I, Margaret Brown Dunlap, a citizen of the United States, residing at Lubbock, in the county of Lubbock and State of Texas, have invented a new, original, and ornamental Design for a Clothes Hanger, of which the following is a specification, reference being had to the accompanying drawing, forming part thereof.

Fig. 1 is a front elevational view of a clothes hanger, showing my new design; and

Fig. 2 is a top plan view thereof.

Contrasting colors are indicated by shade lines. The rear surface of the design is plain.

I claim:

The ornamental design for a clothes hanger, as shown and described.

MARGARET BROWN DUNLAP.
